ARTHUR E. KEATING AND JOHN A. ANDERSON, OF BRIDGEPORT, CONNECTICUT, ASSIGNEES TO THE BRIDGEPORT HARDWARE MANUFACTURING CORPORATION, OF BRIDGEPORT, CONNECTICUT, A CORPORATION OF CONNECTICUT

HATCHET, HAMMER OR SIMILAR TOOL

Application filed October 24, 1929. Serial No. 402,089.

This invention relates to hatchets, hammers or similar headed tools and to a method of making the same, and has for an object to provide a headed tool wherein the head and handle are each made of a different grade and character of steel, the head and the handle being each made of a grade and character of steel best adapted for the purpose for which it is intended.

10 It is a further object of this invention to provide a hatchet or headed tool wherein the head may be forged of a high grade tool steel which is capable of maintaining a keen cutting edge, while the handle may be separately forged of a high grade of structural steel having great strength and toughness and also in which the head and handle can be separately heat treated according to the character of steel used, to secure their greatest adaptability for the work to be performed by each.

15 It is another object of the invention to provide a hatchet, hammer or similar tool in which the head and handle are so connected that there is no possibility of the head becoming loose on the handle.

20 Still another object of the invention is to provide a construction for this type of device which can be more easily manufactured and at less cost.

25 With the foregoing and other objects in view, this invention comprises certain constructions, combinations and arrangements of parts as set forth, disclosed and claimed in the following specification considered in connection with the accompanying drawings.

30 In the drawings:

Fig. 1 is a side view of a hatchet embodying one form of this invention.

40 Fig. 2 is a back plan view of the hatchet of Fig. 1.

Fig. 3 is a cross section looking in the direction of the arrows on line 3-3 of Fig. 1.

Fig. 4 is a section on line 4-4 of Fig. 1.

45 Fig. 5 shows a view of the head and handle in a position about to be welded together.

Fig. 6 is an end elevation of the handle.

Fig. 7 shows a view similar to Fig. 5 of a modified head and handle, and

50 Figs. 8, 9 and 10 are fragmentary top views

indicating different ways by which the handle may be welded to the head.

In the construction shown the hatchet head 10 includes the cutting edge 11 on one end and the hammer 12 on the other end and if desired there may be a claw 13 provided in one side. This head 10 is preferably made of a high grade tool steel which is capable of maintaining a keen cutting edge at 11. In the form shown in Figs. 1 to 5, which is the preferred form, there is forged integral with the head 10 on the rear edge thereof an ear or lug 14 to which the shank 15 of the handle 16 is to be welded. The shank 15 is preferably made of a high grade structural steel having strength, toughness and resiliency and is better adapted to stand the strains of use as a handle than it would if made of the same steel as the head. The head end of the shank 15 may be of any desired shape in cross section, but is preferably and should be substantially rectangular or oval in cross section, similar to the lug or ear 14 and if butt welded to the lug is placed in contact therewith as in Fig. 5, and is then welded thereto. This can be readily done in an electric welding machine which heats the abutting ends of the lug 14 and the shank or handle portion 15 and forces them together in the welding operation. This operation produces a rib 17 all around the welded joint which is later ground off so that to all appearances the head 10 is forged in one piece with the handle shank 15, and the welded joint is just as strong as if they were forged in one piece.

Altho it is preferred to electrically butt weld the handle to the lug we are by no means limited to but welding. Other ways of welding may be used as shown in Figs. 8, 9 and 10. As shown in Fig. 8 either the end of the handle or the end of the lug may be provided with a substantially V-shaped recess 26 and the other member with a tapered end 27 to fit said recess. Then when properly heated they can be hammered together to produce the weld. This arrangement could also be used for electric welding. Similarly as shown in Fig. 9 the ends of the lugs and handle may be slanting as indicated at 28

so they will overlap and may be welded together in the same manner. In Fig. 10 the overlapped ends are rabbetted as shown at 29 and welded in the same way.

5 The shank 15 extends throughout the entire length of the handle 16 and is preferably substantially I-shaped in cross section with a central plate or web 18 and flanges 19 extending laterally from the opposite sides 10 thereof and from both sides of the web as shown in Figs. 4 and 6, as this gives the greatest strength for the amount of material used and also can be readily forged. For the outer portion of the length of this shank 15 the space between the flanges is filled with a pair of cheek pieces 20, preferably of wood or a suitable non-metallic material to form the grip or handle. On their outer surfaces, they are rounded as indicated in Fig. 4 to 20 form a continuation of the outer rounded surfaces of the flanges 19, and to give a general oval shape to the grip, and the handle is given a graceful longitudinal curvature as shown in Fig. 1, so that it will fit properly 25 in the hand. These cheek pieces are securely fastened on the opposite sides of the shank by suitable rivets 21, giving a rigid, substantially unitary structure. At their free 30 ends, the cheek pieces are preferably projected outwardly somewhat as shown at 22 to give a sort of rounded enlargement or flange at the end to further improve the grip and prevent tool flying from the user's hand.

In the form shown in Fig. 7, the ear or 35 lug 14 has been omitted from the head 23, and the shank 24 is butt welded directly to the rear edge 25 thereof, electric butt welding being preferably used as in the form previously described. In this case, however, it 40 would be better to pre-heat the head 23, as it is a greater mass than the shank, so that the two members or metals at the point of welding may be of the same temperature, thereby insuring a firm and secure joint 45 therebetween.

It is apparent from the above description 50 that this invention provides a tool of this character which is of a very strong construction in which there is absolutely no danger of the head working loose, that the head being of a high grade tool steel will maintain a keen cutting edge for a greater length of service, and that the handle being 55 made of a shank of high grade structural steel, will have greater strength, toughness and resiliency to withstand the strains to which it is put, much greater than if it were made of the same steel as the head.

By this construction as above set forth, the 60 head and the handle can each be made of a steel most suitable for the particular job it has to perform, the head to have the requisite hardness to maintain its keen cutting edge, and the handle to have the required strength 65 and resiliency and toughness, instead of hav-

ing to compromise and lose some of these desirable qualities when both are made of the same grade steel as where the head and handle are forged in one piece. The handle, being made of structural steel has more toughness and resiliency and is not nearly as liable to break as it would if it were made of the grade or character of tool steel best adapted for the head, and vice versa, the head will maintain its keen cutting edge much longer 70 than it would if it were made of the grade or character of steel best adapted for use in the handle. Resiliency is a very desirable feature in the handle as it makes the tool much easier on the hand and arm of the user. 75 With a properly resilient handle less shock from the blow is transmitted to the hand and arm and so the tool is less tiring.

The forging operations are also much easier and much better forgings can be produced by forging the head in one operation and the handle or shank in another than where they are forged in one piece. This is a material advantage even when the head and handle are made of the same grade and character of steel. Further, there is much less breakage and, therefore, less waste in manufacture so that a better article can be produced at less cost. A still further important advantage is that with our improved construction the head and handle can be differently heat treated to secure their maximum adaptability for the work intended. These heat treatments are controlled according to the steels used and the effect or character desired in the different parts. In short, the head and handle may be each separately forged of the steel most adapted for use in these parts and they are separately heat treated after welding according to the steels used and the work they have to perform.

Although the handle has been shown as being of I-shape in cross section, it may be varied in shape and may be elliptical or oval.

Having thus described the invention, what we claim is:

1. A hand tool comprising a striking head, and a forged handle with an I-shaped shank, the head end of said shank being filled in between the flanges on both sides so that this end portion for a distance from its free end is of substantially oblong transverse section so as to provide a body of metal at said end of greater cross section than that of the I-shaped section, said head being a forged head with an integral lug projecting from one side thereof of an oblong cross section substantially the same as the head end of the shank and arranged with its greatest width in the plane of the head, and said free end of the shank being welded to the free end of the lug with the web of the shank extending in the plane of the head.

2. A hatchet comprising a forged handle including a grip portion and an integral

shank of substantially I-shape in cross section, the head end of said shank being filled in between the flanges on both sides so that this end portion for a distance from its free end is of substantially oblong transverse section to provide a body of metal at said end of greater cross section than that of the I-shaped section, said head being a forged head having an integral lug of an oblong cross section substantially the same as that of the head end of the shank projecting laterally from one side edge of the head and arranged with its greatest width in the plane of the head, and said free end of the shank being welded to the free end of the lug with the web of the shank extending in the plane of the head.

3. A hatchet comprising a forged handle of steel characterized by strength and toughness including a grip portion and an integral shank of substantially I-shape in cross section, the head end of said shank being filled in between the flanges on both sides so that this end portion for a distance from its free end is of substantially oblong transverse section to provide a body of metal at said end of greater cross section than that of the I-shaped section, said head being a forged head of a character of steel to receive and maintain a keen cutting edge and having an integral lug of an oblong cross section substantially the same as that of the head end of the shank projecting laterally from one side edge of the head and arranged with its greatest width in the plane of the head, and said free end of the shank being welded to the free end of the lug with the web of the shank extending in the plane of the head.

In testimony whereof we affix our signatures.

ARTHUR E. KEATING.
